UNITED STATES PATENT OFFICE.

WILLIAM ALLEN PENDRY, OF DETROIT, MICHIGAN.

BALANCE THROTTLE-VALVE.

SPECIFICATION forming part of Letters Patent No. 360,170, dated March 29, 1887.

Application filed January 20, 1886. Serial No. 189,207. (No model.)

To all whom it may concern:

Be it known that I, WILLIAM ALLEN PENDRY, of Detroit, in the county of Wayne and State of Michigan, have invented a new and useful Improvement in Balance-Valves, of which the following is a specification.

This invention has for its object to provide a novel and efficient balanced throttle-valve which closes with the pressure of the fluid to be controlled; and it consists in the construction and combination of devices, hereinafter described and claimed, reference being made to the accompanying drawings, in which—

Figure 1 is a central vertical sectional view of a valve embodying my invention, and Fig. 2 a similar view showing a modification.

Referring to the drawings, the letter A represents the shell or casing of a valve, which differs in shape according to the kind of valve desired—as globe, angle, straight-way, &c.

B represents the valve-seat, formed in or on the shell in any known way, and C represents an ordinary cup-valve adapted to close seat B.

C represents a piston supported within the valve C, and may fit said valve steam-tight or loosely, as preferred. The manner in which said piston is supported is immaterial, so long as it is held up within the valve; and I have shown as means for accomplishing this end a stem, J', secured to the inside of the shell below the seat B, and rising through said seat the wings J J, secured to the inner side of the shell below the valve-seat B, extending up through said seat and carrying the piston on their upper ends. These wings and the piston also serve as guides for the valve C.

My invention is designed to apply to valves which close with the pressure—steam or water—which they control, and I represents a passage which leads from the steam side of the valve to the space between the valve and piston. The mouth of this passage I is formed into a valve-seat adapted to be controlled by a secondary valve, H.

The passage I is located at one side of the main valve and passes up through the piston. H represents a secondary valve adapted to

control the passage I, and the main and secondary valves are to be so connected with the lifting mechanism employed, which may be of any known kind, that the secondary valve H will open before the main valve C opens. The mechanism which I have illustrated for this purpose is a lifting-lever, W, fulcrumed at one end, T, to a fixed support, S, and at the other end, T', to a connecting-rod, X.

The valve H is provided with a stem pivoted to the lever W by a pin, U, which passes through the lever and through slots V in the upper end of a lug on the crown of the valve C, whereby the motion of the lever W first lifts valve H and then lifts valve C.

The operation of my invention is as follows: When the lifting mechanism is operated to open the valve, the valve H opens first and steam rushes through passage I into the space between the main valve C and the piston, and exerts an equal pressure upon both sides of the crown of the main valve, so that said valve is only held to its seat by the pressure of steam on the area of the annular ring of said valve, which is slight and easily overcome, so that the main valve can be easily opened; and as the secondary valve H is of small area, it can be easily opened against a high steam-pressure. In closing, the main valve seats first, but without shock, for it is so nearly balanced, and is firmly pressed to its seat as soon as the secondary valve closes.

What I claim as my invention, and desire to secure by Letters Patent, is—

The combination, with a cup-valve, of a piston rigidly supported within the valve and having a steam-passage leading through its supporting-stem to the steam-space of the boiler, a secondary valve adapted to close said steam-passage, and lifting mechanism connected with the secondary valve and cup-valve, whereby the secondary valve lifts before the cup-valve, substantially as described.

W. ALLEN PENDRY.
